Windfrey Casner Nichols, Chicago, Ill., assignor
to La Salle Extension University, Chicago, Ill.,
a corporation of Illinois

Application August 23, 1949, Serial No. 4,665

Term of patent 7 years

(Cl. D64—11)

To all whom it may concern:

Be it known that I, Windfrey Casner Nichols, a citizen of the United States, residing at Chicago, in the county of Cook and State of Illinois, have invented a new, original, and ornamental Design for a Shorthand Machine, of which the following is a specification, reference being had to the accompanying drawing, forming part thereof.

Fig. 1 is a top plan view of a shorthand machine showing my new design.

Fig. 2 is a front perspective view showing my new design for a shorthand machine; and

Fig. 3 is a rear elevational view thereof.

I claim:

The ornamental design for a shorthand machine, substantially as shown.

WINDFREY CASNER NICHOLS.
